United States Patent Office

Des. 187,946
Patented May 17, 1960

187,946

VALANCE

Michael Angelo Susi, Brooklyn, N.Y., assignor to Original Plastics, Inc., Hoboken, N.J., a corporation of New Jersey

Application January 7, 1960, Serial No. 58,956

Term of patent 7 years

(Cl. D47—6)

The figure is a plan view of a valance, showing my new design, on a dark background so as to bring out more clearly the details thereof, a unit of which is repeated lengthwise between the selvage edges of the fabric as shown.

The rear view of the valance is similar to the plan view shown.

I claim:

The ornamental design for a valance, substantially as shown and described.
